10 Claims

ABSTRACT OF THE DISCLOSURE

A portable electroplating kit contained in a carrying case and providing the necessary equipment for a complete plating laboratory and prototype plating machine including a rectifier, a pump, a magnetic stirrer, a source for heat, a storage compartment for accessory equipment and a built-in work surface area. The electronic equipment is housed in an enclosed control panel with appropriate control devices available at the face of the control panel.

The aforementioned abstract is neither intended to define the invention of the application which, of course, is measured by the claims, nor is it intended to be limited as to the scope of the invention in any way.

This invention relates to electroplating and, more particularly, to a kit comprising the essential elements of a plating laboratory.

BACKGROUND OF THE INVENTION

Electroplating is commonly used to coat metals, or suitably prepared non-metals such as ABS plastics, to improve appearance, corrosion resistance, hardness, bearing qualities or increase in dimensions. In this process, the object to be coated is made the cathode and the plating metal is the anode. These electrodes are connected to a source of DC current and placed into a plating bath which contains a compound of the metal to be deposited. When immersed into the bath, referred to as a Hull cell, the metal ions migrate to the cathode surface and are there transformed to the metallic state and attached to that surface. The anode metal is dissolved forming new metal ions. The combination of these two steps results in the transfer of the plating metal from the bulk form of the anode to the form of a coating on the object to be coated.

The plating bath must contain a source of the metallic ions which are to be deposited. Some plating solutions employ only simple salts of the metal, others use compounds in which the metal ions are present as complex ions. Other chemicals are frequently added to the bath to improve conductivity of the bath, influence smoothness, brightness, grain size, porosity, hardness and other properties of the deposited metal. In the plating process it is frequently necessary to apply heat during the operation. With other types of metals, agitation of the plating bath is important in obtaining proper deposition. Furthermore, some plating processes will yield superior results under air pressure bubbling in the solution.

Because of the different requirements, the testing and control of commercial plating solutions was heretofore carried out at a large laboratory facility. Numerous complex tests were made to analyze and evaluate plating solutions to determine its metallic composition. However, such analysis is costly and time consuming. A general evaluation of the plating solution could be made by using it with different types of anodes in an actual electroplating process. However, it is generally impossible to use large scale commercial electroplating installations for testing purposes, and furthermore, such large installations do not have suitable laboratory equipment or analysis.

In addition to solution analysis, it is frequently necessary to test the basic metal for prototype plating. Here

2

again it is too costly and difficult to use a large scale commercial plating installation for such prototypes and, therefore, laboratory testing is generally used.

It is, therefore, an object of this invention to provide a portable plating laboratory.

Another object of this invention is to provide a kit containing the necessary laboratory equipment for plating solution evaluation.

Still a further object of this invention is to provide a portable electroplating apparatus capable of prototype plating of objects.

Yet another object of this invention is to provide a plating kit including, in a portable container, the required variable DC current, a source of heat, a variable speed agitator and a vacuum pressure source.

A still further object of the invention is to provide a portable instrument, including a Hull cell, capable of testing and controlling commercial plating solutions.

A further object of the invention is to provide a portable electroplating apparatus, including a magnetic stirrer as a variable speed agitator.

Another object of the invention is to provide a complete plating laboratory installed in an attaché case and weighing less than twenty-five pounds.

Yet another object of the invention is to provide a portable plating laboratory including a solid state rectifier for providing the required DC current.

These and other objects and features of the invention will become more apparent from the following description of the invention.

BRIEF DESCRIPTION OF THE INVENTION

Briefly, the invention comprises a kit including an attaché case housing all the required apparatus needed for a plating laboratory. The upper compartment includes a source of filtered direct current, a timer, a source for a vacuum, a source of heat and an air pressure source. The lower compartment is used as a work table and includes a magnetic member used as a variable speed agitator. The lower compartment is also used as a storage area for the electrodes, the Hull cell filtering apparatus and other laboratory equipment.

DESCRIPTION OF THE DRAWING

In the various figures of the drawing, like reference characters designate like parts.

In the drawing:

FIG. 1 is a pictorial representation of the complete kit of this invention including accessory equipment;

FIG. 2 is a top view partially cutaway of the kit shown in FIG. 1;

FIG. 3 is a front view of the kit shown in FIG. 1;

FIG. 4 is a block diagram of the electrical equipment included within the kit of this invention; and

FIG. 5 is a circuit diagram of part of the block diagram of FIG. 4.

DESCRIPTION OF THE PREFERRED EMBODIMENT

Referring to FIGS. 1 through 3, wherein like reference numbers refer to like parts, there is shown the portable plating laboratory 10 including a carrying case of the attaché type 12, having an upper portion 14 and a lower portion 16. The two portions are hinged together at 18 and snap into place in an upright position. The case is kept in a closed position when not in use by means of latches 20, 22, hooking onto the protrusions 28, 30. Handle 24 is used to carry the case and tab 26 is used as a lever to open the case when in use. The lower portion 16 includes a hinged cover 32 which, in its lowered position, rests firmly on a molding 34 and serves as a table top.

In its open position, it reveals a storage compartment 36 and an electromagnet 38, to be hereinafter discussed. The upper portion 14 includes a control panel 40 enclosing the electronic circuitry and partly filling the upper portion, the remainder of which is used for storage 44. A clamp 46 is placed within the storage compartment 44 and secured to the carrying case. The clamp 46 is adapted to securely retain a thermometer 48.

The power cord 50 is held in the upper storage compartment 44 and when not in use is secured by retaining strap 52. When released, the power cord 50 may be plugged into a 60 Hz., 110-120 v., AC receptacle. A main switch 54 located on the control panel 40 is then turned on. The switch may include a light thereby indicating that the main power is on.

The upper portion 16 of the carrying case 12 includes a rectifier circuit contained behind the control panel 40 which converts the AC power to a DC value. The DC output is controlled by a control knob 56 on the control panel 40 which can be rotated until the proper current is obtained by reading the ampere setting on the ammeter 58 also contained on the control panel 40. Typically, the DC current is controllable from 0-5 amperes at up to 10 volts. The DC output is available at an anode outlet 62 and a cathode outlet 64 at the center of the control panel 40. The outlets are color coded for ease of operation, the anode being red and the cathode black. A set of color coded leads 66, normally stored in the lower storage compartment 36, is provided for fitting into their respective electrode outlets.

A timer is included under the control panel 40 which is set by control knob 68. When the preset time has elapsed, a bell will ring indicating completion of the time cycle. A pressure pump is also included under the control panel which is capable of providing both air under pressure as well as a vacuum. The amount of pressure or vacuum is controlled by means of the ON-OFF switch 70 on the control panel 40. Air under pressure is available at the outlet 72 while a vacuum is available at outlet 74. The pressure or vacuum is used by insertion of a rubber hose 80 normally stored in the lower compartment 36. If filtering of a solution is required, a Buchner filter assembly 82 can be placed on top of an Ehrlenmeyer flask 84. A vacuum hose 80 is fitted between the filtering funnel outlet 86 and the vacuum outlet 74.

An AC outlet 88 is located on the control panel 40 for insertion of a heater coil 90 used for heating the solution to a desired temperature which is monitored by thermometer 48.

An electromagnet 38 contained within the lower compartment 36 is energized from the AC power source by means of the power cord extension 92 passing from the upper portion 14 to the lower portion 16. The amount of energy to the electromagnet 38 is controlled by the control knob 94 on the panel 40. The electromagnet is used to provide whatever agitation is needed in the Hull cell. The cell with the solution is placed on the table top 32 of the lower compartment 16 over the magnet 38. A small bar magnet 96 is placed into the cell and the control knob 94 is rotated until the bar magnet begins to spin. The rate of agitation may be adjusted by positioning the control knob 94.

A main power fuse 98 and a DC line fuse 100 are located at the left side of the control panel 40. In addition to the above mentioned equipment which is needed for various plating operations, additional accessories may also be included and stored in the upper or lower compartments 44 and 36, respectively. Some of these are shown in FIG. 1 including a flask, pipettes, tweezers, filter paper, pH paper, dropper, pipette filler, stirrer, graduate and sparger. Other equipment which may be found useful for plating purposes could also be included. Beaker 85 and graduate 87 are representative.

In operation, the case is opened, the equipment removed from the storage compartments and placed on

the lower table top. The power cord is plugged into a suitable AC receptacle and the main switch is turned on. The DC control knob 68 is adjusted for proper current and voltage as read on the meters and the color coded leads connected to the anode and cathode outlets.

The Hull cell is fitted with a proper anode and the anode clipped into position. The anodes included with the kit are from the group consisting of cadmium, copper, lead, nickel, tin, tin-lead, and zinc, although additional anodes could be used. The cell is filled with the solution to be tested. An object to be coated is cleaned in an appropriate manner, the cathode clip is attached and the cathode placed into the Hull cell. The timer is set with the timer knob 68. Should agitation be needed, the Hull cell is placed over the electromagnet and knob 94 used to control the rate of rotation as heretofore described. If heat is required, the heater is plugged into receptacle 88 and is applied until the proper temperature is reached. Pressure or vacuum is applied from the outlets 72, 74 as needed. After conclusion of all tests and evaluations, all leads and accessories are cleared from the table top and placed either in the compartment under the hinged table top or in the upper portion 44. The line cord is replaced in its niche and tied by the retaining strap and the attaché case is closed.

Referring now to FIG. 4, there is shown a block diagram of the electronic circuitry included in the kit of this invention. The line cord 102 is inserted into an AC receptacle. In series with the cord is the main power switch 104 and the main power fuse 106. An AC outlet 108 is placed in parallel across the external AC power source but protected by the switch and fuse. An electromagnet 110 in series with a speed control device 112 forms a parallel branch across the protected outlet 108. A vacuum-pressure pump 116 in series with an ON-OFF switch 118 forms a further parallel branch across the protected outlet 108.

A voltage control circuit 120 which varies the magnitude of AC source voltage in series with a step-down transformer 122 forms the final parallel branch. The output from the transformer 122 is rectified in a full wave rectifier 124 whose output is filtered by DC filter 126 to produce the DC output 128. A DC line fuse 130 is serially inserted in the DC line and an ammeter and voltmeter 132 are included to measure the DC output.

Referring now to FIG. 5, there is shown a preferred embodiment of the circuitry capable of performing part of the functions indicated in FIG. 4. The source of voltage 140 passes through the voltage control circuit 142 to the primary 144 of a step-down transformer 148. The secondary 146 connects to a full wave rectifier comprising a diode bridge arrangement of substantially identical diodes 150, 152, 154, 156, each included in a respective arm of the bridge. The secondary winding is connected across one set of diagonals and the output is taken across the opposite set of diagonals. A filter is connected across the output terminals comprising a capacitor 158 in parallel with a resistor 160. Fuse 162 is placed in series with one output line. A voltmeter 164 is located in parallel across the output lines and an ammeter 166 is located in series with one line. The final DC output is taken at 168 and is available for an anode lead connection 170 from the positive terminal and a cathode lead connection 172 from the negative terminal.

The portable plating laboratory heretofore described can be used for quick in-plant analysis of plating solutions, field testing for service groups and for prototype plating. The attaché case can be made of fiberglass and is about twenty inches in length, fifteen inches in width and about six inches in depth. The weight of the kit can be made less than twenty-five pounds.

There has been disclosed heretofore the best embodiment of the invention presently contemplated. However, it is to be understood that various changes and modifica-

tions may be made by those skilled in the art without departing from the spirit of the invention.

What we claim as new and desire to secure by Letters Patent is:

1. A portable kit for use in electroplating, housed in a carrying case and comprising, in combination:

- (a) line means adapted to connect to a source of AC power;
- (b) electromagnetic means connected to said line means;
- (c) pump means connected to said line means for providing a vacuum and a pressure;
- (d) rectifier means coupled to said line means for converting the AC power to a controllable DC power; and
- (e) terminals connected to the output of said DC power for providing connection to an anode and a cathode.

2. A portable kit as in claim 1 wherein the carrying case includes an upper and lower section connected together, said lower section including a detachable cover enclosing a storage compartment, said electromagnetic means being fixed within said storage compartment and said upper section including a control panel enclosing said pump means, said rectifier means and at least a portion of said line means, said terminals being available at the front of said control panel for connection to the anode and cathode.

3. A portable kit as in claim 2 and further comprising:

- (a) voltage control means connected to said line means for varying the AC power supplied to the rectifier means; and
- (b) step-down transformer means having a primary winding connected in series with said voltage control means and a secondary winding connected to said rectifier means, wherein said voltage control means and transformer means are included within the control panel enclosure.

4. A portable kit as in claim 2 and further comprising:

- (a) filter means connected to the output of said rectifier means, and included within the control panel enclosure;
- (b) an ammeter serially connected with one of the terminals of the DC output;
- (c) a voltmeter connected in parallel across the DC output; and

(d) fuse means connected in series with said ammeter wherein said ammeter, voltmeter and fuse means being accessible at the front of said control panel.

5. A portable kit as in claim 2 and further comprising:

- (a) fuse means connected in series with said line means;
- (b) first switch means connected in series with said fuse means;
- (c) second switch means connected in series with said pump means; and
- (d) speed control means connected in series with said electromagnetic means, wherein said fuse means, first and second switch means and speed control means being included within the control panel and accessible to the front of said panel.

6. A portable kit as in claim 2 and further comprising electrical outlet means in parallel with said line means and accessible to the front of said control panel.

7. A portable kit as in claim 2 and further comprising hook means attached to the interior of said carrying case for holding accessory devices in fixed position.

8. A portable kit as in claim 2 and wherein said pump means includes a first outlet providing a vacuum and a second outlet providing a pressure, said first and second outlets available to the front of said control panel.

9. A portable kit as in claim 1 wherein said rectifier means includes a diode bridge circuit arrangement.

10. A portable kit as in claim 2 further including in combination a timing device having a control knob, said timing device being included within said control panel enclosure and said control knob being available at the front of said control panel.
